UNITED STATES PATENT OFFICE.

PETER GOOD, OF WILKES-BARRÉ, PENNSYLVANIA.

STOVE-GRATE.

SPECIFICATION forming part of Letters Patent No. 242,628, dated June 7, 1881.

Application filed April 4, 1881. (Model.)

To all whom it may concern:

Be it known that I, PETER GOOD, of Wilkes-Barré, in the county of Luzerne, and in the State of Pennsylvania, have invented certain new and useful Improvements in Stove-Grates; and I do hereby declare that the following is a full, clear, and exact description thereof, reference being had to the accompanying drawings, and to the letters of reference marked ⁵ thereon, making a part of this specification.

This invention relates to certain improvements in stove-grates, and it has for its objects to provide a grate which can be conveniently manipulated to free the fire-box of ashes, which ¹⁵ will separate the ashes from the unconsumed coal, and which can be applied to any variety of stove, furnace, or range, as more fully hereinafter specified. These objects I attain by the apparatus illustrated in the accompanying ²⁰ drawings, in which—

Figure 1 illustrates a longitudinal sectional view of a stove embodying my invention, and Fig. 2 a perspective view of the front portion thereof.

²⁵ The letter A indicates the body of the stove, which may be of any approved pattern or form and constructed of any suitable material.

B indicates the fire-box, and C the front or stationary section of the grate.

³⁰ The letter C' indicates the movable or bottom section of the grate. This is hinged or pivoted to the rear lower edge of the fire-box, and extends forward under the hearth D of the stove, projecting forward beyond the fire-box.

³⁵ The said lower section of the grate is composed of a series of bars, which may be straight, or curved as indicated in the drawings.

The letter E indicates the ash-pit, located below the grate, as usual, and separated from ⁴⁰ a forward chamber, F, by means of a partition, G, the said forward chamber serving to collect

and hold any superfluous unconsumed fuel that may be shaken off the grate.

The forward edge of the grate rests upon an oscillating lifter, H, which is mounted on a ⁴⁵ transverse shaft, K, located just back of the partition G, and journaled in suitable bearings in the sides of the stove. One of said journals extends outside beyond its bearing and is provided with a crank or bent arm, L, by which ⁵⁰ it may be operated to oscillate the lower grate-section and discharge the ashes from the fuel when desired.

The operation of my invention will be readily understood from the above description and ⁵⁵ is as follows: The fuel in the fire-box rests upon the lower grate-section, as usual. When it is desired to remove the ashes from the fuel, the said lower grate-section is elevated and depressed by oscillating the lifter. This discharges the ashes into the ash-pit, and at the same time delivers any unconsumed coal over the forward edge of the grate into the front receptacle, thus serving as an ash-sifter for saving unconsumed fuel. ⁶⁰

Having thus fully described my invention, what I claim, and desire to secure by Letters Patent, is—

In combination with the fire-box of a stove, the lower grate-section, hinged or pivoted to ⁷⁰ the lower rear edge of the same and extending forward under the hearth, the ash-box, and forward coal-receptacle, and the lifter, the whole arranged substantially in the manner and for the purposes specified.

In testimony that I claim the foregoing I have hereunto set my hand this 23d day of March, 1881. ⁷⁵

PETER GOOD.
